DIE BORING MACHINE

John C. Ewart, Milwaukee, Wis., assignor to A. O. Smith Corporation, Milwaukee, Wis., a corporation of New York

Application March 10, 1950, Serial No. 148,789

10 Claims. (Cl. 77—3)

1

This invention relates to a machine for boring pipe swaging dies and the like.

In swaging pipe from a large diameter to a smaller diameter, for example under the disclosure of U. S. Patent No. 2,247,863, issued to Julius B. Tiedemann on July 1, 1941, it is necessary to employ a pair of complementary arcuate dies adapted to rock longitudinally on the pipe being swaged. Each die is provided with a groove which has a curved tapered portion, for reducing the diameter of the pipe, and a straight untapered portion for straightening and sizing the pipe to final dimensions. The formation of such grooves has heretofore been a very expensive procedure, involving lengthy milling and grinding operations as well as a matching operation to insure identity of form between the grooves of a particular pair of dies.

The principal object of the present invention is to provide a machine which will simultaneously bore arcuate tapered grooves in a pair of pipe swaging dies, thereby eliminating the above mentioned milling, grinding, and matching steps and enabling the grooves to be formed at approximately ten per cent of the previous cost.

Another object of the invention is to provide a die boring machine which is readily adjustable for various sizes of dies and which will bore both arcuate tapered grooves and straight untapered grooves.

Another object of the invention is to provide a boring machine wherein the feed screw for the cutting tool is driven through a universal joint coupling arrangement which permits the boring bar to be adjusted to various oblique and parallel positions for boring different types and sizes of dies.

Another object of the invention is to provide a machine whereby a pair of dies may be bored at the same time and rocked during the boring operation so as to be substantially tangent to each other at the point of cutting, insuring accurate matching of the grooves and eliminating the necessity of a separate matching operation.

Another object of the invention is to provide a die boring machine having inserts which may be used to adapt the machine for boring various types of dies.

The machine, in general, comprises a boring bar adjustably mounted between a pair of rotatable head members, a cutting tool adapted to move along a feed screw on the boring bar and cut matched grooves in an opposed pair of arcuate pipe swaging dies, and cam mechanisms shaped to maintain the dies in contiguous relationship at the point of cutting and cause the

2

grooves to curve in general accordance with the curvature of the die faces. The boring bar may be arranged in either oblique relation with the axis of rotation of the head members, for cutting tapered or conical grooves, or in parallel relation therewith for cutting untapered or cylindrical grooves. In a separate embodiment of the invention, the cam mechanisms are provided with various inserts which enable the machine to bore either dies for use in the cold swaging of pipe or dies of different cross-section used in hot pipe swaging operations.

These and other objects and advantages will be set forth more fully in the following description of embodiments of the invention illustrated in the accompanying drawings.

In the drawings:

Figure 1 is a top plan view illustrating the use of the machine in boring a pair of pipe swaging dies;

Fig. 2 is a side elevation of the machine, partly in section;

Fig. 3 is an end elevation, looking toward the left in Fig. 2;

Fig. 4 is a cross section taken along line 4—4 of Fig. 2;

Fig. 5 is a schematic perspective view of the driving elements of the machine;

Fig. 6 is a detail cross-sectional view of one of the heads, showing the universal joint type coupling arrangement in the cutting tool feed mechanism;

Fig. 7 is a partial top view illustrating the cams and dies as rocked to their position at the beginning of the boring operation;

Fig. 8 is a schematic cross-sectional view of the working portions of a pair of cold swaging dies, illustrating the circular cross section of the grooves when the dies are used in a swaging machine;

Fig. 9 is a view, corresponding to Fig. 8, of a pair of hot swaging dies and showing the generally elliptical cross section of the grooves as distinguished from the circular cross section of the grooves of Fig. 8;

Fig. 10 corresponds to Fig. 9 and illustrates the dies as rocked apart and the pipe as rotated ninety degrees;

Fig. 11 is a partial view of the cam mechanisms of an embodiment wherein the machine is adapted with inserts for boring cold swaging dies; and

Fig. 12 is a view corresponding to Fig. 11 and showing the inserts used for boring hot swaging dies.

55 The die boring machine, as illustrated in the

drawings, comprises a bed 1, a pair of heads 2 journalled at opposite ends of the bed 1 for rotation about a horizontal axis, a cylindrical boring bar 3 pivotally connected between the heads 2, and a suitable cutting tool 4 mounted for movement along a longitudinal groove 5 in the boring bar 3. The dies 6, which are cast with grooves 7 in their arcuate front faces, are arranged in opposed relation longitudinally of the boring bar 3 and adjusted so that the cutting tool 4 may operate to simultaneously bore both of the grooves 7 to final dimensions. The rear portions of the dies 6 are bolted to the vertical front faces of supporting brackets 8 which in turn are bolted to the horizontally disposed U-shaped frames 9 of cam mechanisms to be described subsequently.

Each head 2 is constructed with a generally annular base member 10 and a rectangular plate 11 slidably mounted in dovetailed relation with a corresponding recess in the front face of the member 10. In order to permit the boring bar 3 to assume various oblique and parallel positions as the face plates 11 are adjusted along the recesses in the base members 10, a pair of bearing lugs 12 is rigidly secured to each face plate 11 for pivotal engagement with trunnions arranged on the ends of the boring bar 3.

Referring to Fig. 6, each plate 11 is positioned by means of an adjusting screw 13 which is mounted in a groove 14 in the base member 10 and cooperates with a nut 15 on the plate 11 to move the plate when the screw 13 is turned by the operator of the machine. Although the present structure is adapted primarily for a manual adjustment of the face plates 11 and boring bar 3, various mechanisms, for example a star wheel feed, could be employed to move the plates 11 automatically.

With the above described adjusting arrangement, the boring bar 3 may be placed either in parallel with the axis of rotation of the heads 2, for boring the straight sizing portions 16 of the die grooves 7, or in oblique relation therewith for boring the tapered and arcuate working portions 17 of the grooves 7. Synchronous rotation of the heads 2 causes the boring bar 3 to describe, depending on the adjustment of the plates 11, a single or double cone, a frustum thereof, or a cylinder.

The groove 5 in the boring bar 3 is positioned, with relation to the direction of adjustment of the face plates 11, so that the cutting tool 4 mounted therein will engage the grooved surfaces of the dies 6 and bore the same as the heads 2 and boring bar 3 rotate during a boring operation.

The cutting tool 4 is fed slowly along the boring bar 3 by a feed screw 18 which is arranged in the groove 5 in the boring bar 3 for threaded connection with a nut portion 19 of the cutting tool 4. One end of the feed screw 18 is journalled in a bearing lug 20 on the boring bar 3, and the other end is journalled in a corresponding bearing lug 21 and connected to driving members which, together with the drive for the heads 2, will next be described.

Referring particularly to Fig. 5, the main driving elements of the machine are located in the bed 1 and preferably include an electric motor 22 operating through a suitable speed reducer 23 to drive a shaft 24. The shaft 24 is arranged longitudinally of the boring bar 3 and is journalled in a pair of large bearing brackets 25 which are rigidly anchored in the bed 1 at opposite ends of the machine.

The drive for the heads 2 includes a pair of

spur gears 26 connected at opposite ends of the shaft 24 and operating corresponding idler gears 27 and thus large spur gears 28. The gears 28 are mounted at the outer ends of shafts 29 which are integral with their related heads 2 and are journalled, respectively, in the upper portions of the bearing brackets 25.

One of the shafts 29 is formed with a hollow portion 30 having a sufficiently large diameter to prevent interference with the operation of the flexible coupling arrangement for the feed screw 18. The various pairs of gears 26, 27 and 28 are matched to insure that the heads 2 rotate in exact synchronism with each other.

The feed screw 18 is driven through a gear arrangement comprising a pair of meshing bevel gears 31, with a driving gear 31 mounted on the shaft 24, and a shaft 32 having one end connected to the driven bevel gear 31 and the other end connected to a worm 33. The shaft 32 extends transversely of the machine and is journalled in bearings 34 in the bed 1.

Worm 33 coacts with a corresponding worm gear 35 which is connected at one end of a shaft 36. The shaft 36 extends longitudinally of the machine through one of the bearing brackets 25 to rotate a sprocket 37 and thus drive a chain 38 and a driven sprocket 39.

As shown in Figs. 5 and 6, the driven sprocket 39 is mounted on a shaft 40 which extends axially of the hollow shaft 29 and is journalled in a suitable bearing portion 41 at the outer end thereof. In order to provide a flexible coupling arrangement between the shaft 40 and the feed screw 18, a universal joint 42 is secured to the inner end of the shaft 40 and connected through a stud shaft 43 and a second universal joint 44 to the end of the feed screw 18 which is supported in the bearing lug 21 as previously described.

The stud shaft 43 is formed with a square outer end 45 for slidable driving connection with a corresponding female portion 46 of the universal joint 42. The end of feed screw 18 extends from the bearing 21 through a slot 47 in the face plate 11 and the center opening of the annular base portion 10 of the head 2. These openings, together with the sliding connection in the universal joint 42, permit the face plate 11 to be adjusted, by turning the adjusting screw 13, to cause the boring bar 3 to assume the various degrees of angularity required for boring different types and sizes of dies.

With the described universal joint arrangement, the cutting tool 4 may be fed smoothly and uniformly along the boring bar 3 regardless of the angularity thereof. The rate of feed is preferably made very slow in order to prevent damage to the cutting tool 4 and possible tearing of the metal being bored.

To achieve the desired rate of feed, the reduction gearing is selected to cause the gears 28 and the sprocket 39 to rotate in the same direction but at a slightly different angular velocity, for example fifty and forty-nine revolutions per minute, respectively. These angular velocities are imparted, through the universal joints and shafts previously described, to the boring bar 3 and feed screw 18, with the shaft 40 slipping in the rotating bearing 41 at the rate of one revolution per minute. This one revolution per minute difference between the two velocities is the speed of rotation of the feed screw 18 with respect to the boring bar 3 and is a sufficiently low relative speed to permit the desired slow feed.

The cam mechanisms which rock the dies 6 during boring, in order to cause the portions 17

of the die grooves 7 to be cut to curved form, will next be described. These mechanisms are disposed on opposite sides of a straight track 48 which is shown in Figs. 4 and 7 as centered longitudinally of the machine and securely anchored in the bed 1.

Each cam mechanism comprises a horizontally disposed arcuate cam member 49 which rests on the bed 1 for rocking contact with the track 48, a cam actuator 50 adapted to move along the outer edge of the cam member 49 to rock the same, and a feed screw 51 in threaded engagement with a nut portion 52 of the cam actuator 50. Each feed screw 51 is journaled in bearings at opposite ends of the bed 1 and coacts with the nut portion 52 to move the actuator 50 longitudinally of the track 48.

As best shown in Figs. 4 and 7, each cam actuator 50 is preferably constructed with upper and lower horizontal sides 53, a pair of outer roller members 54, and a centrally located inner roller member 55 which is mounted for engagement with the outer edge of a cam 49. The outer rolls 54 move along the vertical inner surface 56 of an elevated edge portion 57 of the bed 1 and serve to positively prevent the actuator 50 from moving laterally.

To insure against longitudinal sliding of the cams 49 as the cam actuators 50 move along the feed screws 51, curved tracks 58 are secured transversely of the machine at opposite ends of the bed 1. The tracks 58 are engaged by suitable rollers 59 which are mounted at the ends of the cams 49.

The cams 49 are thus confined at their inner edges by the track 48, at their outer edges by the cam actuators 50, and at their ends by the curved tracks 58. Accordingly, the movement of the cam actuators 50 along the feed screws 51 imparts an accurately defined positive rocking motion to the cams 49.

The U-shaped frames 9, which support the brackets 8 and thus the dies 6 as previously described, are bolted at their ends to the cams 49 with which they are associated. The frames 9 bear on the upper surfaces of the elevated edge portions 57 of the bed 1. These surfaces, as well as the surfaces of the bed 1 on which the cams 49 and cam actuators 50 rest, are lubricated to permit smooth movement of the cams 49 and to facilitate transmission of this movement to the dies 6.

The major portion of each cam 49 is curved so that the cams 49 and dies 6 will rock when traversed by the cam actuator 50 and cause the tapered working portions 17 of the die grooves 7 to be bored to arcuate conformation. In boring the straight portions 16 of the die grooves 7, which serve to size the pipe as it leaves the swaging machine described in the U. S. Patent No. 2,247,863 previously referred to, it is necessary that the dies remain stationary. Accordingly, one end 60 of each cam 49 is made relatively straight so that there will be no rocking movement when the cam actuator 50 moves therealong.

The drive for the cam actuator feed screws 51 includes a worm gear 61 secured at one end of a shaft 62 in meshing relation with the worm 33 previously described. The shaft 62, which runs parallel with the shaft 36 through one of the bearing brackets 25, operates through a small spur gear 63 and large idler 64 to drive a gear 65 mounted at the end of one of the feed screws 51. The other feed screw 51 is then driven, in

synchronism with the first, through a pair of sprockets 66 and chain 67.

The gearing used in driving the feed screws 51 is selected so that the cam actuators 50 will be fed at exactly the same rate as the cutting tool 4, and in the same direction. In addition, the cutting tool 4 and the axes of the inner rolls 55 of the cam actuators 50 are initially positioned along a line perpendicular to the axis of rotation of the heads 2. The cams 49 will therefore operate to maintain the dies 6 in contiguous relationship at the point where the cutting tool 4 is operating, causing the cutting tool to concurrently bore the grooves 7 in both dies 6 to accurately matched contours.

The operation of the die boring machine is as follows: assume that a pair of dies 6 has been bolted to the brackets 8 on the cam frames 9 and adjusted so that there is a slight clearance between the adjacent portions of the dies. The cam actuators 50 and cutting tool 4 are next positioned at one end of their courses of operation, for example with the inner rolls 55 in contact with the straight portions 60 of the cams 49. The portions 60 will then be in engagement with the track 48 and the straight sizing portions 16 of the die grooves 7 will be in boring relation generally parallel to each other.

The operator next adjusts the screws 13 to cause the boring bar 3 to assume a position parallel to or coincident with the axis of rotation of the heads 2, with the cutting tool 4 in position to bore the die grooves 7. The depth of the cut, and thus the diameter of the grooves bored, may be precisely regulated by using marks on the base portions 10 of the heads 2 as base points and adjusting the screws 13 until the corresponding ends of the boring bar 3 are predetermined distances from said base points.

The machine is then set in motion and the sizing portions 16 of the die grooves 7 are bored to a cylindrical cross-section corresponding to the cylinder described by the boring bar 3 as the heads 2 rotate. Although the cam actuators 50 move, in synchronism with the cutting tool 4, toward the working portions 17 of the dies 6 as the grooves are bored, the portions 16 will not be bored to arcuate form. This is because the ends 60 of the cams 49 are shaped, as previously described, to prevent rocking movement during this portion of the boring operation.

As soon as the boring of the straight sizing portions 16 of the grooves 7 is completed, the operator stops the machine and adjusts the boring bar 3 for boring the tapered and arcuate working portions 17 of the grooves. This adjustment is made by turning the screws 13 until the boring bar 3 assumes an oblique position corresponding to the desired taper and until the cutting tool 4 is in boring relation with the groove surfaces.

In boring the tapers of dies for large pipes, both ends of the boring bar 3 will be on the same side of the axis of rotation of the heads 2 and the bar will describe a frustum of a cone as the heads 2 rotate. For boring smaller dies, one end of the boring bar 3 may be on the axis of rotation of the heads, so that a cone is described, or the ends may be on opposite sides of the axis and a double cone described.

The machine is then set in operation for the second time, causing the cam actuators 50 and the cutting tool 4 to resume their travel. As the cutting tool 4 is fed toward the unbored portions of the dies 6, it will describe circles of

progressively increasing diameter and the working portions 17 of the die grooves 7 will be bored to conical or tapered shape.

In addition, the movement of the cam actuators 50 along the curved edges of the cams 49 will cause the cams 49 to slowly rock along the track 48 and maintain the dies 6 in contiguous relation at the point where the cutting tool 4 is operating. This causes the grooves 7 to bow in general accordance with the curvature of the die faces.

The portions of the die grooves 7 are thus bored to the desired curved and tapered shape. To prepare the machine for boring a second set of dies, the first set is removed from the machine and the motor 22 reversed, causing the cam actuators 50, cams 49 and cutting tool 4 to resume their initial positions.

It may be desirable, for increased production speed, to provide means to more rapidly return the elements to their initial positions. For instance, the shafts 36 and 62 could be connected through suitable clutches to a separate motor and the cam actuators 50 and cutting tool 4 returned to their initial positions without the necessity of rotating the heads 2.

When used in a pipe swaging machine such as the one described in the patent previously referred to, the adjacent portions of the dies 6 are preferably maintained a slight distance from each other. This is best illustrated in Fig. 8, wherein a pipe 68 being swaged is shown in relation to a pair of cold swaging dies. To provide for this gap, the dies 6 are held a corresponding distance from each other during the boring operation, so that a cross-section of each of the grooves 7 will be slightly less than a semi-circle.

The dies shown in cross-section in Fig. 8 are the type generally used in the cold swaging of pipe, and they may be used in the hot swaging thereof. It is preferable, however, that the dies used in hot pipe swaging be shaped to prevent the hot pipe from being marked by the edges of the grooves 7 as the dies 6 rock against the pipe.

To accomplish this, the dies 6 may be shaped, as shown in exaggerated form in Fig. 9, so that a cross-section of the arcuate tapered portions 17 of the corresponding grooves 7 is generally elliptical in form, with the major axis 69 of the ellipse parallel to the faces of the dies. The first stroke, or rocking, of the dies 6 during the swaging operation will therefore form the hot pipe 68 to a corresponding elliptical cross-section.

As the pipe is fed through the swaging machine described in the patent previously referred to, it is rotated ninety degrees between each rocking stroke of the dies 6. The major axis 70 of the pipe will thus be rotated ninety degrees from the major axis 69 of the die grooves 7, as shown in Fig. 10. Accordingly, the pipe will not be in engagement with the edges of the grooves 7 as the second rocking stroke is performed and there will be no harmful shearing action between these edges and the pipe.

During the second rocking stroke, the pipe is again formed to an ellipse corresponding to the shape of the grooves 7, which in effect rotates the major axis 70 of the pipe ninety degrees. Since the process is repeated for each rocking stroke, the edges of the grooves 7 never shear against the hot pipe and mark the same.

As in the case of cold swaging dies, the straight sizing portions 16 of the die grooves 7 of hot

swaging dies are cylindrical in cross-section, so that the pipe is made perfectly cylindrical by the time it leaves the swaging machine.

In the embodiment of the invention illustrated in Figs. 11 and 12, the track 48 and cams 49 of the die boring machine are provided with inserts so that the machine may be adapted for boring either cold swaging dies or hot swaging dies.

The track inserts comprise a section 71, used for boring cold swaging dies, and a section 72 for boring dies used in hot swaging operations. The inserts 71 and 72 are arranged, respectively, in end to end relation with a shortened main track 48 and are bolted to the bed 1 at the end of the machine corresponding to the straight portions 16 of the die grooves 7.

The cam inserts comprise a pair of cam edge sections 73 for boring cold swaging dies and a corresponding pair 74 for boring hot swaging dies. The pairs of edge sections are suitably bolted in corresponding indented portions 75 at the outer edges of the straight ends 69 of the cams 49.

To bore a set of cold swaging dies, the inserts 71 and 73 are used. The track insert 71 is perfectly straight and is made the same width as the main track 48. The cam inserts 71 are shaped the same as the corresponding portions of the cams described in connection with the first embodiment of the invention. The movements of the cams and dies, and thus the shape of the die grooves 7, are therefore the same as that explained in the description of the first embodiment.

When it is desired to bore a pair of hot swaging dies, the inserts 71 and 73 are removed from the machine and the inserts 72 and 74 are inserted. The major portion of the track insert 72 is made slightly narrower than the main track 48, but the inner end 76 of the insert 72 is progressively widened and is the same width as the main track 48 at the point of engagement therewith.

The cam inserts 74 are made complementary to the track insert 72, so that the cam actuator 50 operates to positively rock the cams along the track.

The operation of the machine, when used with the inserts 72 and 74, is the same as that previously described except that the cams are spread apart from each other as they rock up the rise at the inner end 76 of the track insert 72.

This slight spreading action is transmitted through the frames 9 and brackets 8 to the dies 6, causing the cutting tool 4 to cut a shorter arc 55 in each die and making the tapered working portions 17 of the die grooves 7 shallower than the straight sizing portions 16 thereof. When the dies 6 are used in a swaging machine the distance between the dies is the same as the distance therebetween when the straight portions 16 are bored. Accordingly, the straight sizing portions 16 of the grooves 7 have a circular cross section, when the dies 6 are in a swaging machine, and the tapered portions 17 have the desired generally elliptical cross section described with relation to Fig. 9.

The apparatus described in connection with the embodiments of the invention is operable to bore accurately matched grooves in a variety of types and sizes of swaging dies, which enables these grooves to be formed at a small fraction of their former cost. Since the life of swaging dies is limited, and since the grooves are rebored several times during the life of a pair of dies, 70 this saving in the cost of groove formation may

result in an appreciable decrease in the cost of pipe production.

Although the machine is particularly designed for boring swaging dies, it is operable to bore a variety of objects. Various sizes and shapes of cams may be used to regulate the rocking motion, and various inserts may be used in connection with the cams.

Single tapered articles may be bored in the manner described, and double tapered articles may be bored by reversing the settings of the ends of the boring bar 3 as the cutting tool 4 reaches the converging point of the tapers.

Various embodiments of the invention may be employed within the scope of the accompanying claims.

I claim:

1. In a machine for making tapered or cylindrical bores in dies and shafts and the like, a support with an annular recessed base plate provided on the inner side of each head, a pair of spaced heads journaled in said support, a boring bar pivoted between said heads, a second plate slidably mounted in the recess of the base plate and connected to the boring bar, an adjusting screw threaded into a portion of the second plate member to slide said plate in the recess of the base plate when the screw is turned by the operator to adjust said boring bar to various oblique and parallel positions with relation to the axis of rotation of said head, a cutting tool mounted on said boring bar, a feed screw disposed longitudinally of said boring bar and threadedly engaged with said cutting tool, a flexible coupling arrangement connected to one end of said feed screw, and means to rotate said coupling and heads at different angular velocities and thus cause feeding of said cutting tool along said boring bar.

2. In a machine for making tapered or cylindrical bores in dies and shafts and the like, a support, a pair of spaced heads journaled in said support for rotation about a common axis in synchronism with each other, a boring bar pivoted between said heads, means to adjust said boring bar to various oblique and parallel positions with relation to the axis of rotation of said heads, a cutting tool mounted on said boring bar, a feed screw journaled longitudinally of said boring bar and threadedly engaged with said cutting tool, and means including a pair of universal joints to rotate said feed screw with respect to said boring bar to cause feeding of said cutting tool therealong, one of said universal joints comprising a female portion adapted to receive the square end of a shaft of the outer portion to provide a sliding connection in the joint permitting adjustment of the boring bar to various degrees of angularity.

3. In a machine for boring arcuate grooves in swaging dies and the like, a support, a boring bar mounted in said support, a cutting tool disposed on said boring bar for cutting engagement with the grooved portion of the die to be bored, means to rotate said cutting tool and feed the same along said boring bar, and a cam mechanism to rock said die in accordance with the curvature of said grooved portion and in accordance with the feeding movement of said cutting tool, whereby said cutting tool is maintained in boring relation with said grooved portion and said portion bored to arcuate conformation.

4. In a machine for boring matched arcuate grooves in an opposed pair of pipe swaging dies or the like, a support, a boring bar rotatably mounted in said support, a cutting tool disposed

on said boring bar for cutting engagement with the grooved portions of the dies to be bored, means to rotate said boring bar and said cutting tool and to feed said cutting tool, an opposed pair of cams shaped in general accordance with the curvature of said grooved portions and operably connected with said dies to rock the same, a pair of cam actuators disposed for engagement with their respective cams, and means to move said actuators in synchronism with the feeding of said cutting tool and thus to rock said cams and dies and maintain said dies in contiguous relation at the point of operation of said cutting tool.

5. In a machine for boring arcuate grooves in swaging dies and the like, a support, a boring bar mounted in said support, a cutting tool disposed on said boring bar for cutting engagement with the grooved portion of the die to be bored, means to rotate said cutting tool and feed the same along said boring bar, and a cam mechanism to rock said die in accordance with the curvature of said grooved portion and in accordance with the feeding movement of said cutting tool, said cam mechanism having inserts to provide for the boring of different types of dies.

6. In a machine for making tapered and arcuate bores in swaging dies and the like, a support, a boring bar mounted in said support, means to rotate said boring bar about an axis of rotation oblique to the axis of said boring bar, a cutting tool mounted on said boring bar for cutting engagement with the die to be bored, means to feed said cutting tool along said boring bar, and a cam mechanism to relatively rock said die and said axis of rotation in accordance with the curvature of the groove to be bored in said die and with the feeding of said cutting tool, whereby said cutting tool is maintained in cutting relation with said die and a groove is bored to the desired form.

7. In a machine for making tapered and arcuate bores in pipe swaging dies and the like, a support, a pair of spaced heads journaled in said support and rotated about a common axis in synchronism with each other, a boring bar connected between said heads, means to adjust said boring bar to various oblique and parallel positions with relation to the axis of rotation of said heads, a cutting tool mounted on said boring bar for cutting engagement with the grooved portion of the die to be bored, means to feed said cutting tool along said boring bar, a cam operatively connected with said die and curved in general accordance with the curvature of said grooved portion, a cam actuator disposed to engage said cam, and means to move said actuator in synchronism with the feeding of said cutting tool and thus to rock said cam and die and maintain said cutting tool in boring relation with said grooved portion.

8. In a machine for making accurately matched tapered and arcuate bores in an opposed pair of pipe swaging dies or the like, a support, a pair of spaced heads journaled in said support and rotated about a common axis, a boring bar connected between said heads, means to adjust said boring bar to various oblique and parallel positions with relation to the axis of rotation of said heads, a cutting tool disposed on said boring bar for engagement with the grooved portions of the dies to be bored, means including a feed screw and a universal joint coupling arrangement to feed said cutting tool along said boring bar, a pair of cams shaped in general conformity with the curvature of said grooved portions, and means associated with said cams to move said dies in accordance with

11

the shape of said cams and with the feeding of said cutting tool and thus to maintain said dies in contiguous relation at the point of operation of said cutting tool.

9. In a machine for making tapered and arcuate bores in swaging dies and the like, a support, a boring bar mounted on said support, means to rotate said boring bar about an axis of rotation oblique to the axis of said boring bar, a cutting tool mounted on said boring bar for cutting engagement with the die to be bored, means to feed said cutting tool along said boring bar, and a cam mechanism to relatively rock said die and said axis of rotation in accordance with the curvature of the groove to be bored in said die and with the feeding of said cutting tool, said cam mechanism having inserts to provide for the boring of different types of dies.

10. In a machine for making accurately matched tapered and arcuate grooves in an opposed pair of pipe swaging dies and the like, a support, a boring bar mounted in said support, means to rotate said boring bar about an axis of rotation oblique to the axis of said boring bar, a cutting tool disposed on said boring bar for engagement with the grooved portions of the dies to be bored, means to feed said cutting

12

tool along said boring bar, a track mounted longitudinally of and beneath said boring bar and having a narrow section and a wide section, a pair of opposed arcuate cams operably associated with said dies and disposed to rock on said track, and cam actuator means to rock said cams on said track and maintain said dies in contiguous relation at the point of operation of said cutting tool, with the distance between said dies and thus the depth of the grooved portions depending upon the width of said track.

JOHN C. EWART.
